UNITED STATES PATENT OFFICE

DANIEL CUSHING, OF CAMBRIDGE, MASSACHUSETTS

METALLURGICAL FURNACE

Original application filed July 19, 1926, Serial No. 123,279, and in Great Britain September 26, 1927, now Patent No. 1,703,337, granted February 26, 1929. Divided and this application filed December 12, 1928. Serial No. 325,557.

This application is a division of application Serial No. 123,279, filed July 19, 1926, now Patent No. 1,703,337, of February 26, 1929.

The invention relates to a furnace for metallurgical operations, particularly adapted to the melting or reduction of non-ferrous metals such as copper, brass, bronze, zinc or tin.

It is the object of my invention to improve such a furnace in several important respects, by which improvements the furnace is better adapted to its intended purposes and by which more satisfactory results are attained.

A further object of the invention is to provide improved means for regulating the draft and for permitting interchangeable use of forced or natural draft or any combination thereof.

An important feature of my improved furnace is the provision of a cupola having a bottom member or removable plate which is provided with a refractory lining, commonly fire brick, permanently attached thereto, which bottom member may be moved to open position for dumping and cleaning the furnace without disturbing the lining material supported thereby.

My invention further relates to arrangements and combinations of parts which will be hereinafter described and more particularly pointed out in the appended claims.

A preferred form of the invention is shown in the drawings in which—

Fig. 1 is a side elevation of a metallurgical furnace embodying my improvements;

Fig. 2 is a plan view thereof;

Fig. 3 is a partial sectional elevation, taken substantially along the line 3—3 in Fig. 2;

Fig. 4 is a plan view of the bottom member, and

Fig. 5 is a detail sectional view of a portion of one of the draft regulating devices.

Referring to the drawings, I have indicated a metallurgical furnace comprising a cupola or body portion 10 and a stack 11 connected thereto. The cupola has the usual fire brick lining and is provided with a

charging door 12, a clean-out door 13, a breast block 14 and a tap spout or runner portion 15, all of substantially the usual construction. The breast member 14 is preferably made as a single unit formed of fire brick or other similar refractory material and the opening therein is closed by clay or other material when the metal is not flowing. The cupola 10 is supported upon an annular frame member 10^a, mounted on legs 17. The cupola is provided with a plurality of spaced tuyère blocks 20 (Fig. 3) each having a tuyère opening 21 formed therein. Each block 20 preferably consists of a single piece of refractory material with a tuyère opening 21 formed directly in said material.

As indicated in Fig. 3, these blocks are preferably of rectangular shape and of such dimensions that the tuyère opening in each block is surrounded by a substantial thickness of refractory material. The size of the tuyère opening is determined largely by the operating conditions and particularly by the kind and structure of metal to be reduced.

An outwardly projecting cylindrical member 23 is provided for each tuyère block 20 and forms a portion of the tuyère structure. A fan F or other source of air under pressure is connected by pipes 24, 25 and 26 to the cylindrical member 23 previously described, and the tuyère blocks are thus supplied with air under any desired pressure, depending upon the size and speed of the fan F.

Provision is also made for the introduction of air under natural draft. In the drawings, I have shown the outer ends of the cylindrical projections 23 as provided with a series of spaced air openings 30 (Fig. 5) which are covered by a cylindrical cap or sleeve 31 having a series of similar air openings 32. The openings 32 are spaced apart so that the imperforate portions of the cap between the openings are of sufficient width to close the openings 30 when aligned therewith.

The end portions 33 of the caps 31 are preferably provided with central openings 34 through which the interior of the furnace may be inspected and each opening 34 is 100

preferably closed by a glass or mica disc 35. Each cap 31 may also be provided with a slot 36 and binding screw 37 by which said cap may be held in desired angular adjustment.

5 The screws 37 may be taken out and the caps 31 may be removed if access to the tuyère openings is desired. It is sometimes desirable to reduce the number of tuyère openings in use, and the removal of the caps 31 permits selected tuyères to be conveniently closed by inserting temporary plugs therein.

10 The lower part of the furnace is of a special construction which forms the subject matter of the claims retained in my original application. For closing the lower end of the cupola or body portion 10 of my improved furnace I provide a bottom member 40, pivoted at 41 to bearing members or ears 42 extending downward from the annular bottom frame member 10^a of the furnace. The member 40 is provided with an upwardly extending annular flange 45 and with an outwardly extending annular rim portion 46. The flange 45 is also provided 15 with an internal rib 47, for a purpose to be described. The outwardly extending rim portion 46 engages the annular base member 10^a and forms a sealing member therefor.

20 A cross bar 48 extends between the arms 49 on which the bottom member is pivoted, and the member 40 may be swung upward to operative position by placing a lever 50 under the member 40 and over the cross bar 48. When the bottom member 40 has been 25 moved to raised position, a post or brace 51 may be inserted to hold the member 40 in such raised or operative position. A chain 52 may be provided to limit the swinging downward movement of the bottom member.

30 When in operation, the bottom member 40 supports a lining preferably formed of fire brick 54 fitted within the circular flange 45 and having grooves 55 in their edge portions adapted to fit over the rib 47. A layer 35 of heat insulating material 56 is preferably provided between the bottom member 40 and the bricks 54. The lining is thus retained firmly in operative position by the rib 47 and may be additionally secured within the flange 45 by suitable cement if desired.

40 The bricks are so firmly secured in position that the bottom member 40 may be swung to operative or inoperative positions without disturbing the lining of the bottom member 40.

45 After the bottom member has been raised to the position shown in Fig. 3, the opening around and above the flange member 45 may be closed by a suitable sealing material 57, such as fire clay or cement, this sealing material being easily displaced as the bottom member swings downward. The upper face of the fire brick 54 and of the sealing material 57 preferably forms an inclined sur-

50 face substantially at the level of the tap opening 58, so that the molten metal in the bottom of the furnace may flow freely to the tap spout 15.

55 In actual operation, I have found that a bottom member constructed as above described, is extremely well adapted for melting non-ferrous metals, especially when in the form of light chips or scrap. In such operations I preferably use a pitch coke or 60 a coke of high compressive strength and 65 substantially free from impurities.

70 I attain very important advantages by the combination of forced and natural draft which I have shown and described. With 75 this combination, I may close the openings 30 and operate on forced draft entirely, or I may uncover the openings 30 partially, thus modifying and reducing the forced air pressure to any desired extent. I may also 80 shut off the fan F and operate entirely under natural draft, regulating the natural draft by the angular positions of the caps 31.

85 This double control of the air supply has 90 been found extremely useful in carrying out metallurgical operations upon non-ferrous metals, where it is extremely essential that the draft be closely regulated and that excessive draft be avoided.

95 Having thus described my invention and the advantages thereof, I do not wish to be limited to the details herein disclosed otherwise than as set forth in the claims, but what I claim is:—

100 1. A metallurgical furnace comprising a cupola having a plurality of spaced tuyères 105 therein, means to supply air under pressure above atmospheric to said tuyères, said cupola having also a passage to admit air under natural draft to said tuyères, and means to open and close said natural draft passages, and to vary the area of the air-admitting openings to said passages.

110 2. A metallurgical furnace, comprising a cupola having a plurality of spaced tuyères 115 therein, means to supply air under pressure to said tuyères, means to supply air under natural draft to said tuyères, and means to vary the proportion of air under pressure and air under natural draft admitted to 120 said tuyères, said latter means comprising a hollow cylindrical projecting portion having a plurality of openings in the cylindrical outer wall thereof and a cap fitting said cylindrical projection and having a corresponding number of openings therein, said openings being separated by imperforate portions and said cap being angularly adjustable on said cylindrical projection.

125 3. Means to admit air to a tuyère comprising a substantially cylindrical structure with a cylindrical outer wall provided with a plurality of spaced openings, and a regulating cap fitted to said cylindrical wall of 130 said cylindrical structure and having im-

perforate portions of approximately the same width as the spaced openings in said cylindrical wall, said perforate portions being spaced apart by openings in said cap adapted to register with said first named spaced openings.

4. Means to admit air to a tuyère comprising a substantially cylindrical structure with a cylindrical outer wall provided with a plurality of spaced openings, and a regulating cap fitted to said cylindrical wall of said cylindrical structure and having imperforate portions of approximately the same width as the spaced openings in said cylindrical wall, said imperforate portions being spaced apart by openings in said cap adapted to register with said first named spaced openings, and the end wall of said cap having provision for fire inspection therein.

20 5. A metallurgical furnace, comprising a cupola having a plurality of spaced tuyères therein, means to supply air under pressure to said tuyères, means to supply air under natural draft to said tuyères, and means to vary the proportion of air under pressure and air under natural draft admitted to said tuyères, said latter means comprising hollow projecting portions and members adjustably mounted thereon and effective to control the admission of air under natural draft to said tuyères, said members being also bodily removable from said hollow projections to give access to said tuyères.

35 In testimony whereof I have hereunto affixed my signature.

DANIEL CUSHING.
